OXIDATION OF OLEIC ACID

Daniel Swern and Hogan B. Knight, Philadelphia,
Pa., assignors to the United States of America
as represented by the Secretary of Agriculture

No Drawing. Application July 29, 1949,
Serial No. 107,625

4 Claims. (Cl. 260—406)

(Granted under the act of March 3, 1883, as
amended April 30, 1928; 370 O. G. 757)

1

This application is made under the act of March 3, 1883, as amended by the act of April 30, 1928, and the invention herein described, if patented in any country, may be manufactured and used by or for the Government of the United States of America for governmental purposes throughout the world without the payment to us of any royalty thereon.

This invention relates to a process of oxidizing oleic acid to produce 9,10-dihydroxystearic acid and aliphatic monobasic and dibasic carboxylic acids having an average chain length of about nine carbon atoms in a simple and economical manner.

Oleic acid is a readily available material which on oxidative cleavage yields 9,10-dihydroxystearic acid and valuable monocarboxylic and dicarboxylic aliphatic acids containing about nine carbon atoms in the molecule such as pelargonic and azelaic acids, respectively. Such monobasic acids are useful, for instance, as intermediates in the production of artificial flavors, while the dibasic acids are valuable intermediates in the manufacture of plastics, synthetic fibers and lubricants. Both monobasic and dibasic acids containing about nine carbon atoms are also useful as intermediates in the production of plasticizers and in chemical syntheses.

According to the invention, oleic acid, dissolved in a lower saturated aliphatic carboxylic acid containing a catalytic amount of a suitable metal salt selected from the group consisting of the organic and inorganic salts of cobalt and manganese dissolved therein, is contacted with a free oxygen-containing gas such as air and free oxygen, as for example, by blowing the solution with a stream of the free oxygen-containing gas, at a temperature ranging from about room temperature (25° C.) to the boiling point of the said lower saturated aliphatic carboxylic acid, for a length of time sufficient to cause oxidative cleavage of the oleic acid, thereby converting the oleic acid to oxidation products including 9,10-dihydroxystearic acid in admixture with monocarboxylic and dicarboxylic aliphatic acids having an average chain length of about nine carbon atoms, such as pelargonic and azelaic acids, respectively. These resultant reaction products are then recovered by any suitable procedure, for example, by removal of the solvent medium by distillation and resolution of the distillation residue into its components by conventional procedures.

Any lower saturated aliphatic carboxylic acid, of a concentration adapted to dissolve oleic acid may be used as the solvent in our process. Suit-

2

able acids include, for instance, such lower saturated aliphatic monocarboxylic acids as formic, acetic, propionic and butyric acids. The use of acetic acid, however, is preferred in view of its ready availability and the superior results obtained therewith. Aliphatic anhydrides, such as acetic or propionic, are also satisfactory solvents.

The proportions of oleic acid and solvent acid may be varied within wide limits although it is usually desirable to use about 1 to 2 parts, by weight, of solvent acid for 1 part of oleic acid, since within this dilution range the viscosity of the solution is sufficiently low to permit a fine dispersion of the oxygen-containing gas.

15 The catalysts adapted for use in the process are the salts of cobalt and manganese, the most effective catalysts being the cobalt salts, which are therefore preferred. Any organic or inorganic acid salt of these metals which is soluble to an appreciable extent in the reaction mixture may be used; however, it is usually advantageous to use a salt of the acid employed as the solvent medium in the process. Although smaller amounts of the catalyst may be used, maximum yields of the desired cleavage products are usually obtained on oxidation of solutions containing about 0.25 percent, by weight, of the metal, based on oleic acid. Larger proportions of the metal salt, for instance, in amounts corresponding to about 1.25 percent of the metal component, based on oleic acid, do not appreciably increase the yields of the cleavage products.

20 The oxidation may be conducted at ordinary room temperature or with application of heat up to the boiling temperature of the solvent medium.

35 The preferred temperature range is approximately from about 50° to 100° C. Thus, at about 25° C. the reaction proceeds relatively slowly, and the yields of cleavage products are relatively low. When the process is conducted at the boiling

40 point of the solvent, the yields are usually lower than those obtained at temperatures within the preferred range. Furthermore, when operating in the preferred temperature range, not only is a large part of the uncleaved portion of oleic acid

45 converted to 9,10-dihydroxystearic acid, which is a valuable by-product of the process, but also only a small proportion of the oleic acid originally employed is oxidized to polymeric products.

50 The following examples illustrate the invention:

Example I

A solution consisting of 1200 g. oleic acid, 2400 ml. of glacial acetic acid and 12.7 g. of cobalt acetate (0.25% Co, based on oleic acid) was blown

3

with a stream of finely dispersed oxygen at 65° C. for 256 hours. The acetic acid was then recovered by distillation at a pressure of about 50 mm., yielding a cherry red, viscous oil as a residue. This was refluxed for four hours with an excess of 3 N aqueous sodium hydroxide, and the resulting soap solution was acidified with an excess of dilute sulfuric acid and extracted with ether. The ether solution was washed with water until acid free, and most of the solvent was removed by distillation. The concentrated ether solution was then cooled to about 0° C., and the precipitated 9,10-dihydroxystearic acid was filtered off and washed with CCl_4 ether to remove soluble, colored impurities. The yield of 9,10-dihydroxystearic acid, M. P. 124° to 128° C., was about 10 to 15%. The combined ether solutions were then evaporated, and the residue was converted to methyl esters by refluxing it for six hours with a large excess of anhydrous methanol (2ml./g.) and catalytic quantities of 95% sulfuric acid. The acid was neutralized by the addition of solid sodium bicarbonate, and the excess methanol was recovered by distillation. The residue was rendered anhydrous by adding benzene followed by azeotropic removal of water. The benzene was evaporated, and the residual methyl esters yielded, on vacuum distillation, a fraction boiling at about 70° C./4 mm. to 160° C./04 mm. which consisted almost exclusively of cleavage products. (Saponification number 414-433; calculated for a 50:50 mixture of methyl pelargonate and dimethyl azelaate, 423.) The yield was about 65%.

Example II

The oxidation procedure of Example I was conducted at about 25° C. for 500 hours, a 10% yield of 9,10-dihydroxystearic acid, and a 25% yield of cleavage products (saponification number, 380-395) were obtained as described in the foregoing example.

Example III

The oxidation procedure of Example I was conducted at the boiling point of acetic acid for 128 hours. A 10% yield of 9,10-dihydroxystearic acid and a 45% yield of cleavage products (saponification number 355) were recovered as described in Example I.

Example IV

The oxidation procedure of Example I was conducted at 100° C. for 264 hours. No 9,10-dihydroxystearic acid was obtained, and a 65% yield of cleavage products (saponification number 483) were recovered as described in Example I.

In the foregoing examples, the oxidation can

4

also be effected by blowing a corresponding amount of air in lieu of oxygen through the solution. Similar results are obtained by analogous procedures using another lower aliphatic acid such as formic, propionic or butyric acid in place of acetic acid, and equivalent amounts of other cobalt salts such as cobalt oleate, cobalt linoleate, cobalt chloride and the like in place of cobalt acetate. When a manganese salt is used as a catalyst in place of a cobalt salt the reaction rate is decreased and the yields of the cleavage products and 9,10-dihydroxystearic acid are lower.

The process of this invention is applicable to other monounsaturated, long-chain aliphatic acids such as elaidic, palmitoleic, petroselinic, vaccenic, ricinoleic and the like, and their functional derivatives in which the double bond is unaffected.

We claim:

1. A process of producing 9,10-dihydroxystearic acid comprising contacting oleic acid, dissolved in about twice its weight of acetic acid containing an amount of cobalt acetate corresponding to at least 0.25% of cobalt on the basis of the oleic acid, with a free oxygen-containing gas at a temperature of about from 50° to 100° C., thereby converting the oleic acid to oxidation products containing 9,10-dihydroxystearic acid in admixture with monocarboxylic and dicarboxylic aliphatic acids having an average chain length of about nine carbon atoms.

2. The process of claim 1 wherein the contacting is effected by blowing the oxygen-containing gas in a stream through the oleic acid solution.

3. The process of producing 9,10-dihydroxystearic acid by the method of claim 1 and isolating the formed 9,10-dihydroxystearic acid.

4. The process of producing a mixture of monocarboxylic and dicarboxylic acids having an average chain length of about nine carbon atoms by the method of claim 1 and esterifying the acids of the resulting mixture.
